UNITED STATES PATENT OFFICE

WILLIAM ISAACS, OF STRUTHERS, AND ELMER E. McVEY, OF YOUNGSTOWN, OHIO

FURNACE

Application filed April 19, 1929. Serial No. 356,518.

Our invention relates more particularly to open hearth regenerative furnaces such as are commonly employed in the steel industry although it is equally applicable to other forms of regenerative furnaces intended for other purposes.

Open hearth regenerative furnaces as usually constructed comprise the furnace proper including the hearth, a set of regenerators disposed near each end of the furnace at a lower level than its hearth and passages respectively extending therefrom through which the incoming heated air and gas is conducted to the furnace from one set of regenerators and the waste gases discharged from the furnace into the other set of regenerators. In accordance with the usual practice the chambers of each set of regenerators are either disposed side by side and thus separated by a single partition wall or spaced apart for a short distance and thus separated by two walls with a space or opening therebetween, but the air and gas passages leading from the chambers to the furnace are customarily separated by but a single wall irrespective of the particular arrangement of the regenerator chambers with the result that the heated gas which is under considerable pressure, tends to leak through any cracks or openings in the wall and mix with the air in the air passage. As both the air and gas are in highly heated condition, ignition immediately takes place in the air passage and the wall adjacent the cracks where the gas has leaked through is burned away gradually in cone-shaped depressions, while, additionally, this premature ignition and burning of the air and gas in the air passage renders proper control of the furnace impossible with consequent enhancement of operating costs and generally unsatisfactory operative results.

While initially the leakage of the gas through the division wall between the gas and air passages may be relatively slight it proceeds in progressively greater amounts as time goes on for the burning away of the wall adjacent the leaks and consequent formation of the cone-shaped depressions or holes therein facilitates the passage of the gas so that

more and more of it leaks through and is burned in the air passage while the wall, in turn, burns further and further away until it becomes so honey combed either locally or throughout its entire extent from the regenerators to the throat of the furnace that it is useless for its intended function, and the furnace must then be shut down and kept out of commission until the division wall can be repaired or replaced.

A principal object of our invention, therefore, is the provision of means for preventing the leakage of gas from the gas passage to the air passage in an open hearth or like furnace whereby premature ignition of the air and gas in the air passage with consequent erosion of the division wall between the passages and shortening of its effective life as well as loss of operative control of the furnace is avoided.

Further objects of the invention are the provision of means for the purpose aforesaid which may be readily employed in open hearth or like furnaces without material alteration of the usual structural arrangements thereof, which do not materially increase the initial cost of installation and which are entirely satisfactory for the performance of their intended functions.

Other objects, advantages, and novel features of design, construction and arrangement comprehended by our invention are hereinafter more particularly pointed out or will be apparent from the following description of an open hearth furnace constructed in accordance with the invention and illustrated in the accompanying drawings.

As our invention relates more particularly to those portions of the furnace, considered as whole, which concern the conduction of the air and gas from the respective regenerative chambers to the throats of the furnace adjacent the ends of its hearth, and as regenerative furnaces are usually similar at both ends, we have, in the accompanying drawings, shown only those parts adjacent one end of the furnace which are necessary or desirable for a proper comprehension of our invention.

In the said drawings, Fig. 1 is a central,

vertical, longitudinal section through the end of the furnace substantially on the line 1—1 in Fig. 2, and Fig. 2 is a horizontal section through the regenerative chambers, gas and air passages and adjacent parts substantially on the plane of line 2—2 in Fig. 1. Like symbols of reference are used to designate the same parts in both figures.

The furnace, as shown, save in particulars 10 hereinafter mentioned, is of ordinary construction comprising a hearth 1 adjacent and above the end of which is disposed the outwardly and upwardly inclined gas port 2 from which the gas is discharged towards 15 the hearth and which communicates at its outer end with a downwardly extending neck 3 in turn communicating by a laterally directed horizontal passage 4 with the gas regenerative or checker chamber 5 which, in this 20 instance, is disposed laterally of the furnace hearth and bounded by walls generally designated as 6. Above the gas port 3 is disposed the usual air port 7 through which the air is discharged toward the hearth and which 25 near its outer end communicates with downwardly extending necks 8 on either side of the furnace in turn communicating at their lower ends with the air passage 9 which extends for a short distance parallel to the gas 30 passage and may then be turned slightly angularly forward towards the center of the hearth to enter the air regenerative or checker chamber 10 bounded by walls generally designated as 11 and located alongside of but 35 nearer the center of the furnace than the gas checker chamber 5, the adjacent walls of these chambers being, in the present instance, spaced apart for a short distance although frequently in open hearth furnace construction 40 these chambers are merely separated by a single division wall instead of two separate spaced walls. The inner ends of the gas and air passages beneath the furnace proper are deepened so as to provide the usual slag 45 pockets P, P' to receive and hold dust, particles of metal or the like entrained with the outgoing gases and from these slag pockets the bottoms of the passages are respectively sloped upwardly as at 13 and 14 so as to enter 50 the regenerative chambers a considerable distance above the floors thereof in the ordinary way and within the chambers is disposed the usual checker work, designated as 15. The hearth of the furnace is supported 55 on pillars and beams and the walls by buckstays in the customary manner and as these parts are well understood and may be of any desired or preferred construction and arrangement no extended reference thereto is 60 required.

In accordance with our invention instead of providing a single solid division wall between the gas and air passages 4 and 6, we provide at this point two longitudinally spaced, generally transversely extending

walls 16 and 17 to respectively form the adjacent side walls of these passages and dispose between these walls for the purpose of supporting them a plurality of transversely spaced, vertically extending supports 18 which may desirably consist of steel I-beams of suitable width or depth and of sufficient length to extend the height of the walls 16 and 17 or even, as shown in Fig. 1, to a point a little above their upper ends. The webs of these supports are cut out at spaced points as best shown in Fig. 1 so as to provide in each support a series of vertically spaced openings 20 and thereby permit a free circulation of air from one end to the other of the passage or space 21 between the walls 16 and 17, whereby any gas which may leak through the wall 16 will be carried away through this passage and thus positively prevented from finding its way into the adjacent air passage 6.

In the particular furnace we have chosen to illustrate the regenerative air and gas chambers are spaced apart and, consequently, the space 22 between the adjacent chamber walls forms in effect a prolongation of the passage 21, and this arrangement is usually preferable as it permits a very free and unrestricted air circulation in the passage 21 which, as shown, extends entirely across the furnace and opens to the atmosphere as at 21' on the side of the furnace opposite the checker chambers.

We have shown the checker chambers as arranged laterally of the furnace and the passage 21 thus extending in a direction generally transverse of the furnace but in some furnaces the checker chambers are located more or less in longitudinal alignment with the hearth and beyond the ends of the furnace. In such cases, of course, the passage 21 between the walls 16 and 17 defining the air and gas passages will also extend in a generally longitudinal instead of in a transverse direction and will thus open out at the end corresponding to the end 21' at some point beneath the furnace hearth so that the requisite air circulation through the passage can be maintained at all times.

As a further precaution against the leakage and consequent loss of air or gas through the air and gas passage walls we prefer to face or sheath the same on their outer surfaces throughout or substantially throughout their extent with boiler plate or other suitable metal sheathing. This sheathing is shown at 23 on the outer adjacent faces of the walls 16 and 17 and also at 24 on the walls 16' and 17' on the opposite sides of the respective passages. The provision of this sheathing also to some extent enhances the rigidity of the walls and by assisting in the prevention of air or gas leakage through any of them tends to a reduction of the operating cost of the furnace.

As in spite of the utmost precautions which can be taken, the erosive effects of the highly heated incoming air and gas and also of the outgoing spent gases upon the walls of the 5 air and gas passages ultimately render these walls unfit for further service so that their replacement is required, we therefore prefer when constructing the furnace to provide at the upper outer corner of each of the side 10 walls of the passages at its point of juncture with the roof arch, an angle 25 of steel or other suitable metal throughout the length of the wall to assist in supporting the arched roofs of the passages when the side walls are 15 torn down preparatory to their replacement.

Thus in accordance with our invention the entrance of gas from the gas passage to the air passage while the gas is passing from its checker chamber to the furnace is entirely 20 prevented with consequent avoidance of pre-ignition in the air passage and resulting loss of operative control of the furnace. Additionally, the constant circulation of air through the passage 21 tends to keep the adjacent walls cool and thereby enhances their 25 useful life while any gas which may in some way leak through the gas passage wall into the passage 21 is carried off and dissipated to the surrounding atmosphere outside of the 30 furnace. It will further be apparent to those skilled in the art that the initial cost of a furnace of given capacity is not materially enhanced by the inclusion of our improvements while its operative life is thereby materially 35 lengthened, the cost of repairs and replacements lessened and a satisfactory and efficient operative control assured.

While we have herein illustrated and described with considerable particularity one 40 form of open hearth furnace constructed in accordance with our invention, we do not thereby desire or intend to limit or confine the use thereof solely to a furnace of that type as the principles and advantages of our in- 45 vention may be readily embodied in furnaces of other types if desired without departing from the spirit and scope of the invention as defined in the appended claims.

Having thus described our invention we 50 claim and desire to protect by Letters Patent of the United States:

1. In a regenerative furnace having separate air and gas regenerators adjacent each of its ends, walls extending from each of said 55 regenerators and defining separate air and gas passages and slag pockets between the regenerators and the furnace throat respectively adapted to conduct air and gas thereto, the walls most nearly adjacent each other 60 being spaced apart to provide between said passages and pockets a passage open at both ends and extending throughout their length.

2. In a regenerative furnace having separate air and gas regenerators adjacent each 65 of its ends, walls extending from said re-

generators and defining passages adapted to separately conduct air and gas from the regenerators to a point beneath the end of the furnace, the adjacent passage walls being separated to provide a 70 space between said walls throughout their length and means disposed in said space operative to support said walls and having openings whereby air can circulate through said space. 75

3. In a regenerative furnace having separate air and gas regenerators adjacent each of its ends, walls extending from said regenerators and defining passages adapted to separately conduct air and gas from the regenerators to a point beneath the end of the furnace, the adjacent passage-defining walls being separated throughout their length to provide an open ended space between said walls and means operative to support said 80 walls comprising a plurality of spaced I-beams having perforated webs disposed in said space whereby air can freely circulate between the walls throughout the length of said space. 85

4. In a regenerative furnace having separate air and gas regenerative chambers adjacent each of its ends, walls extending from said chambers to a point beneath the end of the furnace and defining slag pockets and air 90 and gas passages respectively extending thereto from said chambers, those of said walls which are most nearly adjacent being spaced apart throughout their length to provide a passage disposed between said slag pockets 95 and open at its ends adapted to permit a circulation of air between said walls from one end of the passage to the other. 100

In witness whereof we have hereunto set our hands this 16th day of April, A. D. 1929. 105
